Primary Examiner — Kimberly Barnes(74) *Attorney, Agent, or Firm* — Ryan T. Grace; Advent, LLP(57) **CLAIM**

The ornamental design for a protective pad array, as shown and described.

DESCRIPTION

FIG. 1 is a front view of a protective pad; and, FIG. 2 is a perspective view of the protective pad shown applied to an example environment with a portion of the design removed.

Portions of FIGS. 1 and 2 are shown in evenly spaced broken lines illustrating portions of the article and environmental subject matter that form no part of the claimed design. The dash-dot-dash boundary lines represent boundaries of the claimed design and form no part thereof.
